UNITED STATES PATENT OFFICE.

ROBERT B. LONGSTRETH, OF COLUMBUS, OHIO.

HINGED COVER FOR BILLS OF FARE.

SPECIFICATION forming part of Letters Patent No. 650,759, dated May 29, 1900.

Application filed October 4, 1899. Serial No. 732,549. (No model.)

To all whom it may concern:

Be it known that I, ROBERT B. LONGSTRETH, a citizen of the United States, residing at Columbus, in the county of Franklin and State 5 of Ohio, have invented new and useful Improvements in Hinged Covers for Bills of Fare, of which the following is a specification.

My invention relates to hinged covers for bills of fare and other uses, my object being 10 to provide a cover or temporary binder for use upon tables in hotels, restaurants, and other places, having a simple and inexpensive construction, whereby a bill of fare may be easily and quickly secured between the two folding 15 members or removed and replaced by another with equal facility and speed.

The primary object of my invention is to provide such a removable cover or temporary binding with a hinge connection of simple 20 form, whereby each member or board of the cover shall have a pivotal bearing wholly independent of the other member, the pivotal points being confined to the ends of each leaf or member of the cover.

It is one purpose of my said invention also 25 to provide a hinge connection for a cover or temporary binder which can be formed in a single piece, so that the complete article comprising both covers and their connection will 30 consist practically of three parts only. This feature of my invention comprises also the provision of a continuous integral channeled or concaved surface on the rearward side of the connecting-hinge and extending from end 35 to end of the same to retain in place an elastic binding-cord or similar device which lies in the central fold or crease formed in the paper and keeps it in proper position, while it allows its ready removal and the insertion 40 in its place of another.

My invention also comprises other novel features, all of which will be fully explained in the following specification and then particularly pointed out and defined in the claims.

For the purposes of the following description reference is had to the accompanying drawings, in which—

Figure 1 is a perspective view showing a cover or temporary binder constructed according to my invention. Fig. 2 is a transverse section on an enlarged scale. Fig. 3 is a detail perspective view of the hinged con-

nexion. Fig. 4 is a similar view of the two leaves, showing their ribbed portions; and Fig. 5 is a detail section taken on the line 55 55 of Fig. 2.

The reference-numeral 1 in said drawings indicates either one of the two covers or leaves, the other leaf or cover section being a duplicate. These cover-sections are of a 60 size adapted to the bill of fare or other matter which is to be inclosed between them. They are preferably formed of nickelized aluminum, though I may also use any other metal or any material that is suitable for the 65 purpose. Each cover-section 1 is of a thickness to impart the necessary strength and stiffness. Upon its connected edge each cover-section is provided with a rib 2, which is nearly circular in cross-section and of a diameter considerably exceeding the thickness of the cover, of which it is an integral part. It extends nearly from end to end of said cover-section, its ends being near the end edges of the latter and at equal distances 75 from the same. Each rib 2 is flush with the inner surface of the cover-section of which it forms a part, the excess of its thickness, as compared with that of the cover or leaf, projecting from the outer surface of the latter. 80

The reference - numeral 3 indicates the hinge connection. It consists of a single piece having a length equal to that of the cover and is preferably, though not necessarily, constructed of the same material. It is 85 provided with two semicircular or nearly, semicircular channels 4, separated from each other by a central rib 5 and having such length as to admit the ribs 2 upon the cover-sections between lugs 6, which lie at the ends 90 of said channels 4. These lugs correspond in form and diameter to the shape in cross-section of the ribs 2, and they are flush at their outer surfaces with the end edges of the cover-sections. A nearly-central opening is 95 formed in each lug 6, registering with a screw-threaded opening in the end of the rib 2, which lies adjacent to or abutting against said lug. A pivot-pin 7, having a plain cylindrical portion 8, is passed through each lug 100 and screwed firmly into the end of the rib 2. These pins are headless, and their ends are flush, or nearly so, with the outer ends of the lugs 6.

The rearward or outer face of the hinge connection 3 is formed with a longitudinal central channel or concave surface 9, extending completely from end to end of the hinge. 5 This channel lies directly in line with the rib 5 upon the inner face, which separates the channels 4 from each other. Said rib also separates the lugs 6 at each end of the hinge connection, and a rubber cord 10 or other suitable fastening when applied will lie upon the rib 5, pass between said lugs 6 at each end of the hinge, and lie centrally in the channel 9. A bill of fare having a central fold or crease can be readily slipped under said elastic cord 15 and drawn into place with the cord in its fold, or it can be withdrawn and another substituted, the operation requiring only an instant.

The cover or binder described and shown is simple in construction and can be economically produced. The form of the hinge connection provides for the retention of the elastic binder or fastening in a central longitudinal line on both outside and inside, so that the sheet held by it will not easily become displaced. The surfaces of the cover-sections can be utilized for advertisements and ornamented in any manner preferred.

While I have described the invention as especially adapted to covers for bills of fare, 30 it is evident that it may be used as a temporary binding for any other material.

Having thus described my invention, what I claim, and desire to secure by Letters Patent of the United States, is—

35 1. A cover for bills of fare or other material, comprising two cover-sections, a hinge connection of a length equal to that of the cover-sections and formed integral at its extremities with perforated lugs and with longitudinal channels between said lugs in which the inner edge portions of the cover-sections are seated, and pivot-pins passing through said lugs into said cover-sections, substantially as described.

45 2. A cover for bills of fare and other purposes, comprising two cover-sections and a hinge connection in a single piece, having a length equal to that of the cover and provided upon its rearward or outer face with 50 a central, longitudinal channel coextensive with the length of said hinge connection, substantially as described.

55 3. A cover or temporary binder having a rigid connection for the two cover-sections provided on its outer face with a central lon-

gitudinal channel to receive an elastic cord or binder, substantially as described.

4. A cover, or temporary binder for bills of fare and other matter, comprising two cover-sections and a single rigid hinge connection 60 therefor, the latter being provided at each end with two lugs to receive pivotal bearings for the ends of said cover-sections, and its exterior face having a longitudinal channel to receive an elastic binding-cord or endless 65 band which lies in said channel and between the two lugs at each end of the hinge connection, substantially as described.

5. A cover or temporary binder for bills of fare and other material, comprising two cover-sections each having a rib on one edge extending nearly to the end edges, and a hinge connection in a single piece having two parallel channels to receive said ribs and lugs at the ends of said channels having openings to 75 receive the plain ends of pins which are tapped into the ends of the ribs, said channels and lugs being separated by a narrow space and the exterior face of the hinge connection being concaved or channeled longitudinally to receive an endless rubber band or elastic cord which lies between the lugs projecting from the other face of said hinge connection, substantially as described.

6. A cover or temporary binder for bills of fare, comprising two cover-sections each having a nearly-circular rib projecting above its outer flat face and flush with the inner face, its ends lying near the end edges of said cover, and a hinge connection in a single 90 piece coextensive with the length of the hinged edges, of the cover-sections, its inner face having two parallel channels and a lug at each end of each channel, said channel and lugs being separated by a central rib and its 95 outer face being concave from end to end, to receive an elastic cord which lies between the two lugs at each end and in the fold of the bill of fare, pins being passed through openings in the lugs and screwed into the ends of the ribs on the cover-section, substantially as described.

In testimony whereof I have hereunto set my hand in presence of two subscribing witnesses.

ROBERT B. LONGSTRETH.
